HOUSING FOR A POWER LAWN MOWER

Ralph A. Czerwonky, Barrington, Ill., assignor to Sunbeam Corporation, Chicago, Ill., a corporation of Illinois

Filed Dec. 23, 1960, Ser. No. 63,320

Term of patent 14 years

(Cl. D40—1)

FIG. 1 is a perspective view of a housing for a power lawn mower embodying my new design, the wheels and fragmentary handle shown in broken lines being included for illustrative purposes only;

FIG. 2 is a front elevational view thereof;

FIG. 3 is a top plan view thereof; and

FIG. 4 is a left side elevational view thereof.

The characteristic feature of my design for the lawn mower housing disclosed resides in the motor shroud in association with the lower portion of the housing, as shown.

I claim:

The ornamental design for a housing for a power lawn mower, substantially as shown and described.
